UNITED STATES PATENT OFFICE.

HARRY WONG, OF DULUTH, MINNESOTA.

ALARM CLOCK.

Application filed February 28, 1925. Serial No. 12,193.

To all whom it may concern:

Be it known that I, HARRY WONG, a citizen of China, residing at Duluth, in the county of St. Louis and State of Minnesota, have invented certain new and useful Improvements in Alarm Clocks, of which the following is a specification, reference being had therein to the accompanying drawing.

This invention relates to improvements in alarm clocks and has special reference to electrical connections for same for controlling mechanism apart from the clock.

The principal object of the invention is to provide simple and practical means whereby the predetermined operation of the alarm clock may be made to control electric energy imparted to another object, such for example as lighting or cooking utensils.

Another object is to provide novel and convenient means for the positive setting of the clock whereby the desired predetermined duration of time of operation of the secondary device may be accomplished.

Other objects and advantages of the invention will appear in the further description thereof.

Referring now to the accompanying drawing, forming part of this application, and in which like reference characters indicate like parts:

Figure 1 is a wiring diagram of the electrical connections with the clock;

Figure 2 is a face view of the clock mechanism with the clock dial removed;

Figures 3, 4 and 5 are successive steps in the circuit making and breaking device within the clock; and

Figure 6 is a side elevation of the setting and electric circuit control cam.

1 represents the circumferential wall of a common circular alarm clock to one inner peripheral face of which is attached the insulated switch block 2, pivotally carrying, as at 3, the switch arm 4, by the swinging of which either one of the two electric circuits subsequently described may be opened or closed, or both allowed to remain open.

A common electric socket 5 is installed on the outer circumferential edge of the clock into which any desired electric circuit may be plugged, as, for example, one controlling the lamp 6. One wire 7 of the light circuit leads into the socket 5 and is connected to the terminals 8 and 9 of the switch 2, and the other wire 10 of the light circuit extends from the socket 5 to the terminal 11, thence

by means of the wire 12 to one side 13 of the circuit control mechanism within the clock.

The opposite side of the circuit control within the clock comprises the flat resilient member 14 to the binding post of which is attached the wire 15 leading to the terminal 16 upon the lower end of the switch 2. Intermediate of the terminals 8 and 16 is the blank terminal 17, while intermediate of the terminals 9 and 11 is the blank terminal 18; these blank terminals being for engagement with the switch arm 4 when the circuits are inactive.

19 represents the frame of the clock works, upon the side of which adjacent the switch 2 is mounted a strip of insulation indicated at 20 upon the lower end of which and spaced outwardly therefrom is securely fastened the spring terminal 14 as at 21, the binding post of said terminal being indicated at 22. This spring terminal is preferably long and flat, carrying strips of insulation upon both sides thereof, except upon the extreme free end where it is intermittently engaged by the flat contact member 23 carried upon the rockable arm 24 pivoted upon the insulated strip 20 as at 25. This rockable arm is held normally in the position shown in Figure 2 of the drawings by means of the spiral spring arm 26, and the contact 23 is slidably engaged at all times upon the plate 27 upon the insulated strip 20, and the wire 12 being connected to this plate and the terminal 11 of the switch 2 forms a circuit intermediate of same.

Now, when the insulated arm 24 is swung downwardly against the action of the spring 26 by the arm 28, the contact between the point 23 and the free end of the arm 14 will be opened; that is to say, disengaged, so that the arm 14 may drop below the point 23, and the elevation of said arm depends upon the action of the arm 29 which is an extension of the alarm spring bar 30 controlled by the axial action of the alarm gear wheel 31 common in all such clocks.

This mechanism is adjustable and operates in every respect in the usual manner, its action simply affecting the resilient terminal member; that is to say, this member 14 remains in its depressed circuit broken position, except when lifted by the action of the functioning of the alarm mechanism, and, when this functioning takes place as heretofore described, resulting in the raising

of the free end of the terminal 14, the arm 24 will instantly jump with the contact 23 beneath the free end of the terminal 14 by the action of the spring 26, thus closing the connection between the terminal 14 and the connections carried by and beneath the arm 24.

The arm 28 is normally retained in a position contrary to that shown in Figure 1 in the act of holding the arm 24 away from the terminal 14 with the contact point 23 out of engagement with said arm. This action of the arm is accomplished by the spiral spring indicated at 32, the arm being held as shown by the action of the setting mechanism mounted concentric with the hand shaft 33 of the clock, which I will now proceed to describe, it being apparent that the arm 28 is formed integral with a similar divergent arm 34 which is controlled by the mechanism about to be described.

A circumferential gear dial 35 is frictionally mounted upon the hand shaft 33 of the clock. Upon this dial are annularly disposed equally spaced figures from 1 to 12 corresponding to the hours of the clock, and upon the hub of the hour hand 36 of the clock and in diametrical alignment therewith is a small pointer 37 the terminus of which registers with the graduations of the numbers above mentioned and this pointer I prefer to have colored red or made attractive in some other manner.

The rotating of the dial 35 for setting purposes is accomplished by the spindle 38 extending radially in respect to the face of the clock and laterally beyond the circumferential edge of same where it is equipped with a suitable thumb head 39. The inner end of this spindle is equipped with the small beveled gear 40 which meshes with the cogged circumference of the dial 35 when the spindle is forced inwardly against the expansive influence of the helical spring 41, the pinion 40 being normally out of engagement with the gear as is obvious.

The sleeve hub 42 of the dial 35 carries upon its lower end the cam disc 43 which has a notched or cut-out portion 44 into which the downwardly bent terminal 45 of the arm 34 drops radially in respect to the disc by the action of the spring 32 when the opportunity is presented by the rotation of the dial.

This dropping in action is illustrated in Figure 3 of the drawings and at which time the end of the arm 34 mounts the downwardly stepped arcuate extension 46 of the cam 43. As the cam is further rotated the arms 28 and 34 are forced away from the axial center of the clock by the downwardly turned end 45 of the arm 34 rubbing against the stepped edge 47 adjacent the arcuate step 46 until it reaches the outer circumference of the cam 43 where it remains until

the completion of another revolution thereof. It is to be understood that the free end of the arm 28 is down beyond the free end of the arm 24 during the time the free end of the arm 34 is following the outermost circumferential extremity of the cam, but since this latter drops into the notch 44 the free end of the arm 28 carries the free end of the arm 24 away from the spring terminal 14 so that the latter may drop into its lowermost position and during the process of shoving the levers 28 and 34 away from the clock shaft they are simultaneously raised somewhat by the arcuate step being arched upwardly so that when the free end of the lever 34 drops off the end of the arcuate step 46 the free end of the lever 28 will fall again behind the free end of the lever 24, there being a small brass wearing plate 48 on top of the lever 24 for such scraping contact with the downwardly bent terminal of the lever 28.

Thus we have means whereby the predetermined setting of the dial 35 may be made to close the circuit control mechanism at any desired time after the tripping of the alarm mechanism, irrespective, of course, as to the sounding of the alarm or not.

50 represents the pointer for the alarm setting mechanism and 51 the retension dog of the alarm mechanism under which the notched sleeve 52 rotates, holding the spring bar 30 downwardly until the dog drops into the notch provided for same within the sleeve, this being common.

Now when the alarm is set by the manipulation of the shaft thereof say for five o'clock a. m. and the switch bar 4 is in the position shown in Figure 1 it being desired that the light 6 shall be turned on for a given length of time after the alarm goes off, the dial 35 is also set to such time as it is desired to have the light shut off, say at 5:30 o'clock a. m. Thus the dial 35 will be set until the indicator 37 is at the 5:30 o'clock mark.

With the clock set in this manner, as the hour of five o'clock in the morning approaches, the alarm mechanism will function, raising the free end of the spring terminal 14 which will scrape it past the upwardly arched end of the flat terminal 23 so that the latter will jump back in under the free end of the spring terminal 14, thus closing the light circuit as illustrated by the diagram in Figure 1. Then as time progresses and 5:30 o'clock arrives, the cam 43 will have rotated to that point where the arm 34 will jump into the notch 44, thereby carrying with it the arm 28, and when the latter engages the free end of the arm 24, the circuit will be opened as previously described by drawing the free end of said arm 24 out from under the free end of the spring terminal 14.

It is obvious that in place of a light some other form of electrically operated means may be similarly controlled for example a heating unit for cooking or other purposes may be turned on and off by the action of the clock.

Now should it be desirable to prevent the clock functioning in respect to the circuit just described the switch arm 4 may be turned to parallel position with the switch block 20 resting upon the points 17 and 18 when no functioning of the circuit would result; whereas should it be desired to operate the light irrespective of the functioning of the clock the switch lever is drawn to the extreme opposite position to that shown in Figure 1, when the circuit 7 and 10 will be shorted through the switch bar as is obvious, and the common alarm mechanism of the clock used separately or in conjunction as desired.

Having thus described my invention, what

I claim and desire to secure by Letters Patent, is:

1. The combination with an alarm clock having an electric circuit cooperatively associated therewith and a switch therefor, of a setting dial concentric with the hand shaft of the clock and normally rotated thereby, a cam cooperatively connected with the dial, means intermediate of the cam and the switch whereby the latter is controlled, and means at the side of the clock and externally thereof for manually setting the dial.

2. A device of the character described comprising an alarm clock, an electric circuit cooperatively associated therewith, means operated by the alarm for closing the circuit and manually set means concentric with the hand shaft of the clock and operated thereby for opening the circuit.

In testimony whereof I hereunto affix my signature.

HARRY WONG.
